UNITED STATES PATENT OFFICE.

WILLIAM C. BLASKE, OF CHICAGO, ILLINOIS, ASSIGNOR, BY MESNE ASSIGNMENTS, TO
HEAT SAVER COMPANY, OF CHICAGO, ILLINOIS, A CORPORATION.

FUEL-SAVING DEVICE.

1,134,943.

Specification of Letters Patent.

Patented Apr. 6, 1915.

Application filed November 3, 1913. Serial No. 799,044.

To all whom it may concern:

Be it known that I, WILLIAM C. BLASKE, a citizen of the United States, residing at Chicago, in the county of Cook and State of Illinois, have invented new and useful Improvements in Fuel-Saving Devices, of which the following is a specification.

The present invention relates to new and useful improvements in fuel saving apparatus.

In the operation of the ordinary stove or furnace, two distinct processes are involved. First, there is the combustion of the fuel by the combination of the carbon therein with the oxygen admitted in the draft. In addition to this combustion, however, there is a process of distillation whereby large quantities of combustible gaseous products are evolved from the fuel by the heat of the fire. In addition to these combustible gaseous products, considerable quantities of smoke, consisting of finely divided unconsumed carbon, issues from the fire, the presence of smoke always indicating the presence of combustible gases. These combustible gases in reality contain a large proportion of the heat units involved in the fuel, yet in the operation of the ordinary stove, they pass up the chimney and are totally wasted.

It is the object of my invention to practically obtain the full benefit of the heat value of the fuel by promoting a complete combustion thereof.

It is another object of my invention to deliver to the highly heated combustible gases evolved from the fire, a stream of pre-heated air having a sufficient heat to produce a combustion of the gases, thus catching these gases, as it were, before they escape, and burning them to obtain their heat values.

My invention contemplates an apparatus whereby a stream of air is first preheated and then efficiently and automatically delivered to the interior of the fuel consumer at or near the point where the combustion gases are evolved from the fuel.

My invention further contemplates an apparatus whereby the stream of air just described, is permitted to flow into the fuel consumer and combine with the combustible gases near their point of evolution of the fuel, the apparatus being so designed as not

to prevent or impede the updraft through the flue.

In the accompanying drawings has been shown the simple and preferred forms of the invention, it being understood, however, that no limitation is necessarily made to the precise structural details therein described, but the right is reserved to any changes, alterations or modifications to which recourse may be had that come within the scope of the present invention, without departing from the spirit thereof.

In the drawings: Figure 1 is an elevation of the stove-pipe having one form of my invention as applied thereto. Fig. 2 is a vertical section of the same. Fig. 3 is a horizontal section taken on the line 3-3 of Fig. 2. Fig. 4 illustrates a slightly modified form of my invention, and Fig. 5 is a horizontal section taken on the line 5-5 of Fig. 4.

It will, of course, be understood that in order to obtain the best practical results with this device, the openings or drafts in the furnace or stove are closed so as to eliminate an updraft through the chimney thus leaving the gas in the flue or furnace beyond or below the preheating chamber, practically quiescent so that the preheated air may flow or travel to the combustion chamber and combine with the combustible material to cause combustion.

Reference now being had to the drawings, wherein I have shown portions of two adjacent sections of a stove-pipe A and B respectively, to which are connected in the usual manner an intermediate section C forming the subject-matter of the present invention. A cylindrical tube 1 is provided having one end thereof corrugated as at 2 whereby the adjacent section A of the stove-pipe may be connected in the usual manner.

An outer cylindrical casing 3 encircles the lower end of the tube 1 and has a greater interior diameter than the exterior diameter of the tube 1, thereby forming an annular space 4 therebetween. A plate 5 is connected to the upper end of the casing 3 by the usual bead connection 6 and is also riveted to the tube 1 by means of the angle plate 7 as shown, thereby providing means for closing the upper end of the chamber 4. Secured to the lower end of the tube 1 as at 8 is a truncated conical section 9 having its lower

or base portion connected adjacent the lower end of the casing 3 as at 10, thereby forming the lower wall of the chamber. Connected to the casing 3 by means of the beaded connection 11 is an inverted conical section 12 having connected to its lower end the cylindrical section 13 which is adapted to be connected to the adjacent section B of the stove-pipe in the usual manner.

10 A damper D is mounted within the tube 1 upon an axle E which is journaled within the structure as shown and provided at one extremity of the axle is an operating lever F. The damper D is slightly less in diameter than the inner diameter of the tube 1 thereby providing a space around the damper when the same is closed to permit the required escape of the gases through the flue. The upper end of the tube 1 projects beyond the casing 3 and has formed therein a plurality of openings 14 and a sliding draft valve 15 encircles the outer periphery of the tube having openings 16 formed therein adapted to register with the openings 14. 20 A handle 17 is carried by the valve 15 whereby the operator may open and close the draft valve. This draft valve is adapted to be opened when the damper D is closed, thereby forming a draft within the flue 30 above the damper to promote the smoke or other gases to escape as is common.

Formed within the casing 3 adjacent the upper end thereof are a plurality of openings 18 which permit the air to enter the chamber 4. The portions of the casing 3 which have been cut away to form the openings are forced inwardly to provide baffle plates 19 which permit the air to enter the openings 18 but direct the same within the upper end of the chamber 4 to prevent the rapid movement of the air into the flue, as will be hereinafter more fully described. The wall 9 closing the lower end of chamber 4 is provided with a plurality of small openings 20 which permit the incoming air to enter the flue in relatively small streams.

The device heretofore described is made of sheet metal and the parts thereof may be readily assembled thereby producing an article which will be cheap to manufacture and which is a great advance in the present art.

In Figs. 4 and 5 of the drawings, I have illustrated a slightly modified form of the invention whereby the device is made of cast iron being adapted to be placed within a sheet metal stove-pipe as shown, or any other stove-pipe flue or breeching. In the modified form of the invention, I have provided an outer casing 21 having connected to the lower end thereof by means of a beaded connection 22 a conical section 23 and secured to the lower end of the conical section is the cylindrical section 24 adapted to be connected to the adjacent section of

the stove-pipe in the usual manner. A cylindrical tube 25 having the same interior diameter as that of the section 24 is provided at its lower extremity with an annular flange 26 which is connected to the upper end of the casing 21 by any suitable or well known means or by rivets 27 as shown. Adapted to be placed within the casing 21 is a cylindrical casing comprising two semi-circular sections 28 and 29 respectively. Each of these semi-circular sections comprises an outer wall 30 and an inner wall 31 which are connected at their upper ends by means of a substantially horizontal wall 32 and their lower ends by means of an inclined wall 33. 80 The opposite ends of each semi-circular section are closed by means of the walls 34. Formed within the outer wall 30 of each section and adjacent the upper ends thereof are a plurality of openings 35 which rest 85 in alinement with corresponding openings 36 formed within the casing 21. Formed integral with the inner wall of each semi-circular section are baffle plates 36 which extend inwardly and upwardly, for directing 90 the air within the upper ends of the chambers 37 formed by the walls of the semi-circular sections. The lower inclined walls 33 of each semi-circular section are provided with a plurality of openings 38 whereby 95 air from the chamber 37 will be permitted to enter the flue. The shaft E carrying the damper D is journaled within the casings as shown, for the purpose which has heretofore been described and the upper cylindrical section 25 is provided with the draft valve 15 as described in the preferred form 100 of the invention.

From the foregoing it is evident that the inner tubes of the devices extend in axial 105 alinement with the stove-pipe or flue whereby the device will not in any way interfere with the escaping gases from the furnace.

It is very desirable that the incoming air be as quiescent as possible in order that the 110 diffusion into the surrounding gases may be more completely and effectively accomplished, therefore the openings within the outer casing of the device are of limited area and the baffle plates adjacent to said openings retard the currents of air by directing the same into the upper end of the chamber. The air while retained within the chambers will be heated by the outgoing 115 heated gases as the chamber encircles the 120 flue and provides a large heating surface.

By providing the inverted cone-shaped chamber G, the preheating chamber is offset from the flue passage so as not to impede or retard the updraft from the furnace or stove 125 which feature is very advantageous when first starting the fire or when the lower drafts in the furnace or stove are opened for the purpose of rapidly increasing the heat 130 within the furnace.

I claim:—

1. In a device of the class described, a smoke flue section, a flue communicating said flue section with the combustion chamber, a casing surrounding said section and forming an air chamber around the flue section, end portions for connecting said casing and flue section, one of said ends being perforated, an inverted frusto conical section connected at one end to said casing and connected at its opposite end to the flue leading to the combustion chamber and means whereby air may be permitted to enter the air chamber near one end and distributed through the opposite perforated end and frusto conical section into the flue leading to the combustion chamber.

2. In a device of the class described, a sectional flue member, the sections of the flue member being in communication by means of an enlarged chamber, a casing surrounding one of the sections and means of communication from the atmosphere through said casing into the enlarged chamber for the purpose set forth.

3. In a device of the class described, a sectional flue member, one of the sections of the flue member having an air pre-heating chamber surrounding the same, means for connecting the sections of the flue member together and providing an enlarged chamber, and means whereby the air from the pre-heating chamber may be permitted to enter the enlarged chamber for the purpose set forth.

4. In a device of the class described, a sectional smoke flue member having a smoke passage way therethrough, a casing encircling one of the sections of the flue member forming an air pre-heating chamber, a frusto conical section connecting the other section of the flue member with the casing

forming an enlarged chamber between the flue sections and means for permitting the pre-heated air to enter into the enlarged chamber for the purpose set forth. 45

5. In a device of the class described, a flue member comprising two sections, a casing connecting the flue sections, air pre-heating chambers inclosed by the casing 50 and retained in position by means of the two sections of the flue, the lower ends of the air pre-heating chambers having openings therein leading within the flue member, baffled inlet openings formed within 55 the upper ends of the air pre-heating chambers and the casing having openings registering with the baffled inlet openings for the purpose set forth.

6. In a fuel saving device of the class described, a flue member comprising two sections, a casing connecting the flue sections, semi-circular air preheating chambers adapted to rest between the flue sections 65 and inclosed by the casing, the outer walls 65 of the air preheating chambers, having baffled inlet openings communicating with corresponding openings formed within the casing, a frusto-conical wall formed by the lower walls of the air preheating chambers 70 having openings therein, the inner walls of the air preheating chambers forming a smoke passage way of the same diameter as that of the flue sections and means whereby 75 the air from the preheating chambers may indirectly enter the smoke passage way for the purpose specified.

In witness whereof, I hereunto subscribe my name to this specification in the presence of two witnesses.
